UNITED STATES PATENT OFFICE.

WILLIAM MUNDELL THORNTON, OF NEWCASTLE-UPON-TYNE, ENGLAND.

ELECTRIC LAMP FOR USE IN MINES.

Application filed September 24, 1928, Serial No. 308,025, and in Great Britain October 11, 1927.

This invention relates to an electric lamp for use in mines and other places where inflammable gas is likely to be present.

It is well known that an electrically-heated filament or like member attains a higher temperature in certain inflammable mixtures than in air. Various forms of gas detecting and measuring instruments have been proposed depending upon this fact and, in different ways, comparing the effects produced by such filaments with those due to a similar filament sealed in air. It is to this broad type of apparatus that the present invention relates more particularly.

15 It has been proposed to provide in a miner's electric lamp two filaments, one whose brightness is not affected by the presence of inflammable gas and the other having in series with it a conductor whose resistance is varied, 20 usually through the well known catalytic effect, by the presence of such gas and to bring both such filaments to the same degree of luminosity by adjusting a resistance in series with the unaffected filament and by so doing 25 obtaining an indication of the proportion of inflammable gas present.

The present invention also depends upon the comparison of the luminosity of two filaments, one affected and the other unaffected 30 by the presence of inflammable gas, but the comparison is actually between a sealed filament and an exposed filament such exposed filament glowing more brightly owing to the burning of the inflammable gas at its surface.

35 The improved lamp according to the present invention comprises two electrically-heated filaments, one sealed in air and normally used for illumination and the other exposed to the atmosphere under test, the two filaments being mounted near each other, a variable resistance contained in the lamp casing and means for adjusting such resistance by the relative movement of two parts of the casing to cause the two filaments to glow with 45 equal luminosity, the amount of such movement indicating the percentage of inflammable gas present.

The sealed and exposed filaments are adjacent to each other in an appropriate chamber 50 in the lamp so that at any time the relative luminosity or the amount of glow or redness of the two filaments can be compared. The normal or zero adjustment of the apparatus is such that the luminosities of the two filaments are equal when the exposed filament is 55 in air. When taken into an atmosphere con-

taining up to certain proportions of inflammable gas the exposed filament will be raised in temperature owing to the combustion of the mixture at its surface and its glow is therefore increased. This is observed and the variable resistance is adjusted to alter the relative values of the currents in the two filaments until their luminosities are again equal. 60

The variable resistance may be in series 65 with the sealed filament those two members being in parallel with the exposed filament in a battery circuit.

Or again, the two filaments may be in series 70 in the battery circuit and the variable resistance may be as a shunt across the sealed filament. After zero adjustment in air increased brightness of the exposed filament in gas is balanced by adjusting the shunt resistance, the movement for making this adjustment 75 indicating the proportion of gas present. In each of these constructions there may be a separate resistance provided for the initial adjustment of the currents through the 80 filaments.

In the accompanying drawings,

Figure 1 is an elevation partly in section of one construction of miner's electric lamp according to this invention,

Figure 2 is a portion of a similar view 85 taken at right angles to Figure 1,

Figure 3 is an under plan of the upper part or cap of the lamp casing,

Figure 4 shows the electric circuit of the 90 lamp,

Figure 5 is a diagram of the circuit in conventional form, and

Figure 6 is a diagram of an alternative circuit.

With reference first to Figures 1 to 4, the 95 lamp as a mechanical structure comprises main parts which are known in miners' electric lamps, namely a casing A containing a battery B and a rotatable cap or casing C on which is mounted a lamp bulb D surrounded 100 by a protective glass E. In the improved lamp there is mounted adjacent to the bulb D containing the sealed filament D¹ another filament F held between two supports F¹ to which filament the atmosphere under test has 105 access through a wire gauze G.

One terminal of each of the filaments D¹ and F is connected to a central pin H which makes contact with the pole B¹ of the battery B. The other terminal of the sealed filament D¹ is joined to a small contact plate D² and the other terminal of the exposed filament F 110

- to another contact plate D^3 , these two plates D^2 and D^3 being mounted on the underside of a plate C^1 of insulating material forming part of the rotatable cap C .
- 5 Held in a recess in this plate C^1 is a spiral resistance J and the second pole B^2 of the battery has contacts which make rubbing connection with the plate D^3 and with the resistance J . One end of that resistance is connected to 10 the plate D^2 and the other end is free. These connections are best seen in Figure 4 where B^3 and B^4 represent the rubbing contacts connected to the poles of the battery.
- If these contacts lie in the gap J^1 shown in 15 Figure 4 the connection to the battery is broken. If the casing be rotated slightly to bring the contact B^3 on to the plate D^2 the sealed filament D^1 will be connected straight across the battery and will be fully bright.
- 20 The exposed filament F will not be in circuit. In this position the lamp functions as a miner's electric lamp in the ordinary way. If the presence of gas is suspected the casing is rotated so that the contact B^4 makes contact 25 with the free end of the variable resistance J in which position the contact B^3 makes connection with the adjacent end of the plate D^3 . In this position the exposed filament F is connected straight across the battery and it will 30 glow more or less brightly according to the amount of gas present. At the same time the sealed filament is connected in series with the resistance J across the battery. If gas is present the exposed filament will be brighter than the sealed filament and the casing is then rotated so as to cut out more and more of the 35 variable resistance J until the filament D^1 glows as brightly as the exposed filament F . At that point the registration of suitable 40 marks on the rotatable cap C with some point on the casing A will enable the percentage of gas present to be read. Any convenient arrangement of scale and pointer may be provided for reading these percentages but in the 45 example illustrated the cap C is provided with a raised scale indicating percentages. As may be seen from Figure 2 there is a raised 0 for zero and screw heads arranged to indicate 1, 2, 3 and 4 by the sense of touch. The 50 registering point on the casing is constituted by a milled head A^2 . This milled head is not permanently fixed on the casing but is mounted on a band or ring A^3 which can be turned relatively to the casing and clamped thereto by the milled head. This arrangement is 55 provided so that the position of the milled head may be altered relatively to the casing for purposes of adjustment to allow for variations in the voltage of the battery.
- 60 The engagement between the casing A and the cap C is by means of a screwthread and to prevent any possibility of the two parts being separated when the lamp is in use in the mine a spring plunger C^2 is mounted on

the cap so that the cap can not normally be 65 turned relatively to the casing for more than one revolution, as the end of the plunger comes in contact with a stop C^3 (Figure 1). This plunger C^2 may be locked in any convenient way (not indicated in the drawings) 70 before the lamp is given out to the miner.

Figure 5 is merely a diagram showing in a conventional and simple form an electric circuit for gas-detecting apparatus according to this invention. In this diagram the 75 exposed filament F^2 is in parallel with the sealed filament D^4 plus a variable resistance J^2 , and the battery B^5 supplies current to both when a switch K is closed. The resistance J^2 is varied to make the brightness of 80 the sealed filament D^4 correspond to that of the exposed filament F^2 when in a gaseous atmosphere and the percentage of gas is read off on a scale moved over by the switch of the variable resistance J^2 . The arrangement 85 corresponds in its essentials to that of the lamp described with reference to Figures 1 to 4, the only difference being that an additional resistance K^1 is provided for the purpose of initial adjustment or calibration before the lamp is issued for use. Such a resistance may be incorporated in the lamp previously described.

Figure 6 is a diagram of an alternative circuit where the sealed filament D^5 is in series 90 with the exposed filament F^3 and has the variable resistance J^3 shunted across it.

What I claim as my invention and desire to secure by Letters Patent is:—

A miner's electric lamp comprising a casing adapted to contain a battery, a cap or cover rotatable relatively thereto, a sealed filament and an exposed filament mounted on said cap, a resistance in the cap, a central contact mounted on the cap connected to one end of said sealed filament and one end of said exposed filament and also to one pole of the battery, two contact plates mounted on the cap the first of such contact plates being connected to the other end of said sealed filament and to one end of said resistance and the other contact plate being connected to the other end of said exposed filament, rubbing connections between the other pole of the battery and the second contact plate and the resistance, whereby relative rotation of said cap and casing will switch the exposed filament on and while it is on will also switch on the sealed filament in series with a variable amount of the resistance, and means whereby the relative rotation of the cap and casing will give an indication of the percentage of inflammable gas present in the atmosphere.

In testimony whereof I have signed my 125 name to this specification.

WILLIAM MUNDELL THORNTON.
